M. C. GARLICK

DUAL POSITION SPRING SWITCH

Filed Oct. 29, 1923

UNITED STATES PATENT OFFICE.

MAURICE C. GARLICK, OF EASTON, PENNSYLVANIA.

DUAL-POSITION SPRING SWITCH.

Application filed October 29, 1923. Serial No. 671,516.

To all whom it may concern:

Be it known that I, MAURICE C. GARLICK, a citizen of the United States, and a resident of Easton, county of Northampton, 5 State of Pennsylvania, have invented a certain new and useful Improvement in Dual-Position Spring Switches, of which the following is a specification.

My invention relates to a spring switch, 10 and more particularly to a dual position spring switch having its switch tongue adapted to be spring held against a rail on either side.

Provision is preferably made in accordance with one form of my invention for having the movement of the spring actuating device controlling the operation of the switch tongue so confined that the switch may be converted at will into a simple or 20 one-sided spring switch, in which the spring tongue is spring held against the rail on one side thereof, and the arrangement preferably is such that when so converted into a simple or one rail type of spring switch 25 the tongue may be spring held against the rail on either of its two sides.

The invention also preferably includes the provision of a dash-pot device adapted to 30 permit rapid closing of the switch tongue under the influence of its spring during the first part of the closing movement, with a slower final closing movement of the switch tongue as it is brought into contact with the rail.

The invention in the preferred form further includes a construction and arrangement of parts adapted to make use of a pull or expansion spring for pulling the switch tongue against the rail in place of 40 the usual push or compression spring, which is readily clogged with dirt, ice and the like.

The pull or expansion type of spring is to a considerable extent self-cleaning, as the closing of the switch tongue against the rail 45 normally occurs practically immediately after the movement of the switch tongue away from the rail, which is accompanied by the opening of the pull or expansion spring, and such spring is not readily clogged with dirt, ice or anything else tending 50 to produce clogging or interfere with proper spring action, and is practically impossible to put out of operation in the course of ordinary use.

Other preferred features of the invention 55 include the provision of a simple means for

adjusting the tension of the spring, and the construction of the parts so that multiple or spare parts can be provided, which are readily assembled and can be replaced 60 in case of wear or for other reasons, in a very simple and efficient manner and with a minimum of expense, time and trouble, and by cheap, unskilled labor, and entirely 65 or practically without the use of tools.

Other objects of the invention will appear in connexion with the following description of an embodiment thereof shown in the accompanying drawings, but it is to be understood that such illustrated embodiment 70 is only for the purpose of affording an understanding of the invention and not for limitation of the invention, which is as broad as my claims, and may be embodied in a variety of forms and involve various 75 modifications and changes of the form shown for illustrative purposes.

In the drawings, Fig. 1 is a plan view on reduced scale with a box or housing containing the switch actuating device as closed, 80 and showing the relation thereof to the track or rails. Fig. 2 is an enlarged partial plan view with the box or housing cover partially broken away. Fig. 3 is a view similar to a portion of Fig. 2, but with the cover 85 entirely removed, and with the rocking lever in the opposite position from that shown in Fig. 2. Fig. 4 is a view similar to a part of Fig. 2, and illustrating the operation of the rocking lever confining 90 means which serve to convert the motion of the switch tongue from dual movement to a one-sided movement, or in other words to convert the switch into a simple one-sided spring switch. Fig. 5 is a longitudinal section on the broken line 5—5, Fig. 2. Fig. 6 95 is a transverse section on the line 6—6, Fig. 2, and Fig. 7 is a longitudinal section through the dash-pot cylinder.

The switch tongue 10 is pivoted at 11 between the rail members 12, 12. Switch tongue 10 is provided on its under side with a downwardly projecting lug 13 which extends through the hole 14 formed in the switch base 15. A box or housing 16 is arranged 100 alongside one of the rails 12, and this box or housing, which is preferably formed as a metal casting, contains the switch actuating device. It is provided with a cover 17 which is received in the groove or recess 18 of the box or housing 16 provided for this purpose. Aligned openings 19, 20 are 105 110

in line with the hole 21 formed in the downwardly projecting lug 13 of the switch tongue 10.

Lid 17 is provided with a perfectly depressed portion 22 in which are formed the holes 23, 24, 25. These holes are adapted to receive the bail 26, one leg 27 whereof is preferably permanently received pivotally in the hole 23 and may be provided at its lower end with a cotter pin 28, which, while permitting the bail to be lifted and turned, serves to prevent its complete removal, except when the cotter pin 28 is taken out.

The opposite leg 29 of bail 26 may be inserted in the hole 24, in which case the bail is inoperative and out of the way and the device is capable of use as a dual spring switch, or the bail may be raised and leg 29 thereof inserted through hole 25, whereby the movement of the actuating parts so arranged is to convert the device into a simple unilateral type of spring switch. These parts will be referred to further in connection with the actuating elements of the device. The portion 22 of lid 17 is preferably depressed as stated in order to receive the cross-connecting portion of bail 26, so that same will not project upwardly beyond the top surface of the lid 17.

The switch actuating means preferably include the rod 30 which extends through the hole 21 in the lug 13 of switch tongue 10, and is provided therebeyond with a hole through which cotter pin 31 is passed, thus affording a simple and readily removable form of connexion for imparting pull from rod 30 to switch tongue 10.

When the device is used as a dual position switch it is necessary to impart pushing action as well as pulling action to the switch tongue 10, and for this purpose a loosely fitting sleeve 32 is provided to surround the rod 30 on the side of switch tongue 10 opposite the cotter pin 31.

The means for actuating members 30 and 32 preferably take the form of a rocking lever 33 having three arms 33^a, 33^b and 33^c. Rocking lever 33 is pivoted at 33^a on a bearing lug 33^c, which extends upwardly from the floor of the housing 16 and which is provided at its upper end with a cotter pin 33^c for holding the lever 33 in position and preventing it from lifting up. The arm 33^a is provided with a horizontal slot 34 through which the rod 30 is passed. The sleeve 32 is shorter than rod 30 and does not extend quite up to the lever arm 33^a on the side thereof near to the switch tongue 10, the rod 30, however, projecting beyond the lever arm 33^a at the opposite side thereof. The lever arm 33^a is preferably provided with substantially circular bearing parts 35, 35 located respectively above and below the slot 34 and a joint is secured between the lever 33^a and the rod 30 and sleeve 32 by

means of the washers 36, 36, which are arranged on rod 30 and distributed as desired between the inner end of sleeve 32 and the cotter pin 37, which is passed through an opening provided in the rod 30 adjacent to the inner end thereof. In the illustrated form three of the washers 36 are arranged on one side to lever arm 33^a and one washer 36 in the opposite side thereof, but the number and distribution of these washers and also the thickness thereof may be varied at will, so as to readily secure a simple and easily changed adjustable connexion between the lever arm 33^a and the switch tongue actuating sleeve 32 in rod 30. The lever arm 33^a is preferably provided near its extreme end with openings for receiving a readily removable pin 38, which serves as an end closure to slot 34 and prevents the parts from becoming disengaged and from getting out of the proper relative positions.

The expansion spring actuating means for operating the switch tongue is applied to arms 33^b and 33^c of lever 33. In the form shown it is provided between the outwardly projecting arms 33^b and 33^c with the straight side actuating portion 39, which is adapted to be engaged by a flanged roller 40 which may traverse track or engaging portion 39 of lever 33 and is stopped at either end 95 by the projecting arm portions 33^b and 33^c respectively. Roller 40 is rotatably secured to the arm 41, which at its opposite end has a hook 42 adapted to hook into a loop or hook 43 on the pull or expansion spring 44. The opposite end of said spring 44 is provided with a similar hook 45 adapted to hook into the preferably round or twisted sidewise projecting loop portion 46 of cross-bar 47. Said cross-bar 47 is adapted to be received 105 in undercut pairs of notches 48, 48 provided in a yoke member 49, the arms 50, 51 of which are detachably pivoted within the extension 16^a of housing 16, and preferably are pivotally received in the lugs 52, 53 formed integrally with the housing walls 110 and provided with a rounded seat for the preferably rounded ends of the yoke arms 50, 51. In this way the yoke can be readily removed or replaced and at the same time 115 when in place may be turned on the pivotal support provided therefor. Means are provided for supplying a downward pivotal movement to yoke 49 so as to support same well above the floor of housing 16 and to thereby protect it from contact with ice or other material freezing within the lower part of housing 16. In the form shown housing 16 is provided with a rib 54 having notches 55, 56 to receive the yoke arm 49 120 at the proper elevation. It will be observed that when the yoke arm is depressed as shown in Fig. 5, the point of connexion of cross-bar 47 is below the pivotal support at 52 for the yoke 49, so that same is past 125

the dead center with respect to the pivoting point of the yoke and there would be no tendency of the yoke to rise due to pull on the spring 44. It will also be observed that 5 spring 44 can be given any desired tension by simply raising the yoke 49 on its pivots and placing the cross-bar 47 in any desired pair of notches 48, the raising of the yoke serving to shorten the distance between the 10 roller 40 and the cross-bar 47, and that when the yoke 49 is depressed it serves both as a holding and a stretching means for spring 44, which may be given any desired tension by placing the cross-bar 46 in the appropriate 15 pair of undercut notches 48.

With the parts in the position shown in Fig. 2, the switch tongue is spring held against the rail on one side and is spring returned into contact with the same rail 20 even if it should be partially opened. When the switch tongue is moved to the position against the opposite rail, as, for example, by means of a wheel flange or an implement such as a switch bar, the lever 33 is turned 25 on its pivot to the position shown in Fig. 3, whereupon the wheel 40 and connected parts are pulled over into contact with the switch arm extension 33^b and with the parts in such position the switch tongue is spring held against the opposite rail.

In order to prevent violent contacting movement of the tongue into engagement with the rail, I preferably provide a dash pot adapted to permit rapid movement of 35 the switch tongue and connected parts during the first operation of either movement, but to permit only a slow closing movement. In the form shown I have provided a dash-pot cylinder 56 pivotally connected at one 40 end as by the removable pin 57 to a portion of the housing 16, and having its piston rod 58 pivotally and detachably connected to the lever 33, as by means of pin 59 passing through the opening 60 in connecting rod 58 and the opening 61 in the lever 33. Pin 59 may have a cotter 62 passing through 45 its lower end, if desired.

The piston rod 58 of dash-pot 56 is provided with a packing gland 63 formed preferably in the screw cover 64 and the piston 65 is provided with one or more relatively small openings 66 preferably located at or near the upper side of piston 65. With this arrangement and with the cylinder 56 only 55 partially filled with liquid, such as oil 67, it will be seen that in the first movement of piston 65 the piston and connected parts may move relatively rapidly since only air is passing through the port or ports 66. Toward the latter part of the piston movement, however, during which time the oil is being forced through the port 66, the movement of piston 65 and connected parts is 60 relatively retarded and while a firm seat 65 of the switch tongue against the rail is per-

mitted under the actuation of spring 44, the spring tongue is not slammed or violently contacted with the rails, so that if any water, for example, is present within the switch there will be no violent or forcible 70 ejection thereof at the time the switch tongue is closed against the rail.

When the bail 26 is positioned as shown in Figs. 2 and 5, the switch operates as already described, that is to say, in "facing point" operation, as a car flange passes over the switch from point to heel thereof, the switch tongue is held firmly against the rail, and there is no possibility of derailment by the switch tongue being moved or shaken 80 out of position between the time of passing of the wheel on the front and back trucks of the car. When the car is passing in the opposite direction, or from heel to point of switch tongue, the first car flange 85 contacting with the switch tongue serves to throw the switch tongue to the opposite position, when it is held by the spring 44, the roller 40 being free to move on track 39 to 90 the opposite end of lever 33.

When switch tongue 10 is initially in the opposite direction, as shown in Fig. 3, with the spring actuated wheel 40 in coaction with the opposite end of the lever 33, the operation of the switch is the same as before, except that in this case the movement of the switch tongue is in the opposite direction. If, however, the bail 26 is raised, turned and lowered, bringing the arm 29 thereof down through the hole 25, said arm 29 serves as a stop for confining the movement of wheel 40 to the arm of lever 33 with which the wheel 40 was in engagement at the time the bail was moved without, however, interfering with the full movement 95 of switch point 10 and lever 33. The interposition of the stop member 29 in the manner described (see Fig. 4) serves to convert the switch from a dual position switch to a single position switch, since while the 100 switch arm 10 and lever 33 may be turned as before to bring the switch tongue 10 into engagement with the opposite rail, the switch tongue cannot remain in such position, but is brought back to its initial position by reason of the presence of stop arm 29 which prevents the roller 40 from shifting to the opposite position along the track 39 of lever 33. With such position of the 105 parts, when the switch tongue is opened by the flange of a passing car wheel (moving heel to point) it is spring returned to its initial position against such rail and in order to throw the switch tongue to the opposite side of the switch it is necessary first 110 to raise the bail 26, replacing it with the arm 29 in hole 24.

It will be seen that a switch constructed as described is very efficient in operation, has an extensive range of utility, and that while 130

the parts are so connected and interrelated that they do not get out of order in use, nevertheless their removal and replacement can be performed practically as a simple manual operation and practically without the use of any tools or at least the very simplest and readily used tools, and that any changes and replacements can be made in a very short interval of time and without any appreciable interference with the traffic.

As stated above, changes and modifications may be resorted to within the spirit of the invention without sacrificing the advantages thereof.

16. I claim:

1. A dual position switch, spring actuating means therefor including a trackway and a roller to travel the trackway, and removable stop means interposable in the path 20. of said roller for converting the device into a single position switch.

2. The combination of switch rails, a switch tongue pivoted therebetween, and means for resiliently holding the tongue 25. against the rail on either side, said means including a double throw lever, a trackway on said lever, a roller to travel said trackway, and pull or expansion spring means applied through said roller to said lever and adapted 30. to pass a dead center with respect thereto.

3. The combination of switch rails, a switch tongue pivoted therebetween, a double throw lever, means of connection between the tongue and lever, and a pull or 35. expansion spring having a traveling connection with said lever and adapted to move past a dead center with respect thereto, whereby the switch tongue may be held resiliently against the rail on either side.

40. 4. The combination with switch rails having a switch tongue pivoted therebetween, of a double throw lever, adjustable means of push and pull connection between said lever and switch tongue, a pull 45. or expansion spring having a traveling connection with said lever so as to be movable past a dead center with respect thereto, and means for adjusting the tension on said spring.

50. 5. In a spring switch, a pivoted switch tongue, a rod fastened thereto and extending generally at right angles to same, a double throw lever pivotally connected to the rod to throw same either way, and expansion spring means having a connexion 55. with the double throw lever adapted to pass dead center in each direction, and means of adjustment for said spring including a pivoted yoke, a plurality of pairs of undercut notches provided in said yoke, and a cross-bar adapted to be received in any pair of 60. said notches and having substantially midway thereof a loop for receiving one end of said expansion spring.

65. 6. Means for imparting lateral spring pull

to a switch tongue comprising a rod extending at substantially a right angle thereto, a rocking lever adapted to throw said rod in either direction, a roller mounted to travel on said rocking lever, a pull or expansion 70. spring attached to said roller, and means for adjusting the tension of said spring comprising a pivoted yoke having a plurality of pairs of notches therein, a cross-bar 75. having a loop substantially midway thereof for reception of one end of said spring and adapted to be placed in any pair of yoke notches, thereby varying the tension of said spring.

7. The combination with switch rails having a switch tongue pivoted therebetween, of a double throw lever, adjustable means of connexion between the lever and the switch tongue comprising a control rod for pulling the switch tongue and a sleeve surrounding the rod for imparting a pushing movement thereto, a pull or expansion spring, a pivoted yoke in which said spring is adjustably mounted and traveling means of connexion between the lever and spring 90. adapted to be moved past a dead center with respect to the lever, whereby the switch tongue is resiliently held against the rail on either side thereof after being first forcibly moved to that side. 95

8. The combination with switch rails having a switch tongue pivoted therebetween, of a push and pull link connected to the switch tongue, a lever having an arm adjustably connected to said link and adjustable both 100. for push and pull, said lever having a trackway at substantially right angles to the said arm, a pull or expansion spring having one end adjustably supported and having traveling means of connexion at its other end 105. adapted to travel on the trackway, whereby the switch arm is resiliently held against the rail on either side of the switch after having been first moved to the said side thereof.

9. The combination with switch rails having a switch tongue pivoted therebetween of spring means normally adapted to resiliently hold the switch tongue against the rail on either side thereof, and manually insertable stop means for confining the movement 110. of the switch tongue so as to cooperate with but one of the switch rails. 115

10. Means for imparting lateral spring pull to a switch tongue, comprising a rod fastened to the switch tongue and extending at substantially a right angle to same, a double throw rocking lever pivotally connected to throw the rod either way, a roller adapted to travel on said lever, a tension-adjustable expansion spring actuating said 120. roller, and a bail adapted to be interposed at will in the path of travel of the roller to thereby convert the double throw switch 125. into a single throw switch.

11. In a spring switch, a pivoted switch 130.

- tongue, a perforated lug extending down therefrom, a rod fastened to the lug and extending at substantially a right angle to the switch tongue, a loose-fitting sleeve on said 5 rod, a double throw rocking lever actuating said rod and sleeve, a roller adapted to travel on said rocking lever, a pivoted yoke having a plurality of pairs of notches therein, a cross-bar adapted to fit in any pair 10 of notches and having a loop substantially midway thereof, a pull or expansion spring having one end detachably connected to said loop, a rod pivoted at one end to the roller and having a loop on its other end to receive 15 the other end of the spring, a buffer pivotally connected to one arm of the rocking lever, and a bail adapted to be interposed in the path of travel of the roller on the rocking lever to thereby convert the 20 double throw switch into a single throw switch.
12. The combination with switch rails having a switch tongue pivoted therebetween, of means normally adapted to resiliently hold the switch tongue against the rail on either side thereof, said means including a lever and a spring having a traveling connexion therewith, and stop means manually insertable in the path of travel 25 of the spring, whereby the rail is temporarily held against but one of the switch rails.
13. The combination with switch rails having a switch tongue pivoted therebetween, of means for retracting the switch tongue against a rail after being moved away therefrom, said means including a double throw lever and a spring having a traveling connexion with the lever, a casing 30 wherein the lever and spring are mounted, and stop means insertable through a wall of the casing for limiting the movement of the traveling spring connexion with respect to the lever.
- 40 14. The combination with switch rails having a pivoted switch arm therebetween of means to resiliently hold the switch against either rail, said means comprising a trackway and a roller and removable stop 45 means interposable in the pathway of the roller to confine the switch movement at will to movement to and from the rail on but one side thereof.
15. In combination, switch rails, a switch tongue pivoted between the rails and having a downwardly extending perforated lug, a rod extending through the hole in the lug and having a cotter pin on one side thereof and a sleeve thereabout on the other side thereof, said sleeve being shorter than the 50 rod, a lever having an arm with a slot therein through which the rod extends and against which arm the sleeve abuts, adjustable stop means between said sleeve and rod and the lever arm comprising washers and a cotter pin, a trackway on the side of the lever fulcrum opposite the said arm and extending at substantially right angles thereto and having stops at its ends, a casing, a yoke pivotally and removably mounted in the 55 casing and said yoke having a series of notches in its upper face, a stop for the yoke in the casing, whereby it is supported with the notches below its fulcrum, a cross-bar adapted to be received in any desired pair 60 of notches, a pull or expansion spring removably attached to said cross-bar at one end, a wheel secured to the opposite end of the spring and adapted to traverse said trackway past dead center on either side, a 65 yoke adapted to be manually inserted through the casing lid to limit the movement of the wheel on the trackway, a dash pot attached to the lever and adapted to slow up its movement as it is moved toward the rail, said dash pot comprising a cylinder partially filled with fluid and a perforated piston within the cylinder.
16. A dual position spring switch, actuating means therefor, a cover for said actuating means, and manually operable stop means projecting to the exterior of the cover for converting the dual position spring switch into a single position spring switch.
- In testimony whereof, I have signed my name hereto.

MAURICE C. GARLICK.
